UNITED STATES PATENT OFFICE.

JACOB S. LAITINEN, OF COLUMBUS, OHIO.

MONKEY-WRENCH.

No. 798,424.

Specification of Letters Patent.

Patented Aug. 29, 1905

Application filed March 30, 1905. Serial No. 252,982.

To all whom it may concern:

Be it known that I, JACOB S. LAITINEN, a citizen of the United States, residing at 599 Henry street, Columbus, in the county of Franklin and State of Ohio, have invented certain new and useful Improvements in Wrenches, of which the following is a specification.

My invention relates to wrenches; and it consists in the use of two fixed shanks provided with the usual fixed jaw and the movable jaw, in means for readily adjusting the movable jaw and securing the same at any desired point, so that the strain produced in the operation of the wrench falls entirely upon the shanks, thereby relieving the adjusting device. The whole is so constructed as to provide a wrench quickly and easily adjusted to any article, is simple and durable, and consists of the parts and has the method of operation hereinafter specifically set forth.

In the accompanying drawings, in which like numerals refer to the same parts throughout, Figure 1 is a side elevation of my improved wrench. Fig. 2 is a plan view of the same. Fig. 3 is a side elevation showing the adjusting pinion-wheel and the means of controlling the same. Fig. 4 shows two views of the pinion and ratchet-wheel. Fig. 5 is the dog, provided with teeth for engaging the ratchet-wheel; and Fig. 6 is a plate confining the ratchet-wheel and providing a bearing therefor.

In my improved wrench, 1 is an upper shank provided upon its inner face with a rack-bar 2, the teeth 3 of which may be either rectangular in side elevation or tapering. 4 is a second shank. At one end the shanks are bound together by the tie 5, which also secures in place upon the shanks the handle 6. Upon the other end of these shanks is mounted a fixed jaw 7.

8 is a movable jaw mounted upon the shanks between the fixed jaw 7 and the handle 6 and adapted to slide between these limits.

9 is a spindle carrying a ratchet-wheel 10 and pinion 11. This spindle fits snugly into an opening (not shown) in one face of the inner side of the movable jaw and is mounted at the other end in the opening 12 in the plate 13. The latter is held in place by screws inserted in the openings 14 and 15. The ratchet-wheel and pinion are mounted rigidly upon the spindle 9; but the spindle itself is free to turn in the bearings described above.

16 is a dog provided with teeth 17 adapted

to engage with the teeth of the ratchet-wheel 10 and hold the same in any desired position. This dog is secured to one of the faces of the movable jaw, as seen in Fig. 3, and is acted upon by a spring 18, seated in a cavity provided therefor in one of the inner faces of the movable jaw. These parts are so placed relatively to each other that when the dog is grasped and forced against the spring, compressing the same, the teeth are thrown out of engagement with the ratchet; but as soon as the dog is released the expansion of the spring forces the teeth thereof again into engagement with the ratchet. The pinion-wheel 11 is adapted to engage with the teeth of the rack-bar 2 as the movable jaw is pushed forward or backward.

The operation of my improved wrench is as follows: To slide the movable jaw nearer to the fixed jaw, it is necessary only to push the movable jaw forward, as in this movement the teeth of the ratchet-wheel run backward over the teeth of the dog, and the pinion engaging with the rack-bar the adjustment forward is quickly accomplished. The movable jaw cannot be moved away from the fixed jaw without releasing the ratchet-wheel, so that any forward movement of the jaw leaves it in a position in which it is locked positively against backward movement. In order to release the ratchet-wheel, the dog is forced against the spring, which movement throws the teeth out of engagement and the ratchet-wheel is free to turn. The movable jaw may now be pushed backward as far as is desired, whereupon the dog is permitted again to engage the teeth of the ratchet-wheel. This is accomplished by the expansion of the spring, which acting upon the dog will unfailingly force it into engagement with the ratchet-wheel as soon as the pressure is removed. The pinion-wheel being carried upon the same spindle with the ratchet-wheel and both being rigidly mounted thereon will turn with the ratchet-wheel and in the same direction whenever the movable jaw is pushed forward or backward. Whenever the ratchet-wheel is locked against backward movement by the dog, the pinion-wheel is also locked. To adjust the wrench to any desired object, therefore, the movable jaw may easily be brought forward by merely pushing thereon or backward by first releasing the dog from the ratchet-wheel and then pushing thereon. When the object is tightly held between the jaws and force is applied to the wrench, it is

seen that the stress falls almost entirely upon the two shanks and that the ratchet and pinion are not under any undue strain. Therefore they are capable of long-sustained usage and on account of the simplicity of their construction will not readily get out of order or in any wise lose their efficiency.

From the foregoing description it is apparent that my improved wrench is simple in construction, easily adjusted to any desired object, and is highly efficient and durable.

What I claim as new, and desire to secure by Letters Patent, is—

1. A wrench, comprising a shank, a second shank, a rack-bar upon said second shank, a fixed jaw, a movable jaw carried by said shanks and adapted to slide thereon, a pinion-wheel mounted in said movable jaw and adapted to engage with said rack-bar, a ratchet-wheel in said movable jaw, a dog mounted within said movable jaw and adapted to engage said ratchet-wheel, a spring mounted in said movable jaw and adapted to hold said dog and ratchet-wheel in engagement, a spindle upon

which said pinion and ratchet are rigidly mounted, and a plate adapted to provide an outer bearing for said spindle and to confine said pinion and ratchet-wheel within said movable jaw.

2. In a wrench, a fixed jaw a movable jaw mounted upon two shanks, a plate secured in one side thereof, a spindle mounted in said jaw and plate, a pinion rigidly mounted upon said spindle and adapted to engage said rack-bar, a ratchet-wheel rigidly mounted on said spindle, a dog mounted within said jaw and adapted to engage with said ratchet-wheel, and a spring mounted within said jaw and adapted to hold said dog in contact with said ratchet-wheel to prevent retrograde movement of said jaw.

In testimony whereof I affix my signature in the presence of two witnesses.

JACOB S. LAITINEN.
